UNITED STATES PATENT OFFICE.

GEORGE L. TYLER, OF TROY, NEW YORK.

CURTAIN-ROLLER SUPPORT.

SPECIFICATION forming part of Letters Patent No. 381,041, dated April 10, 1888.

Application filed May 9, 1887. Serial No. 237,531. (No model.)

To all whom it may concern:

Be it known that I, GEORGE L. TYLER, a resident of the city of Troy, in the county of Rensselaer and State of New York, have invented certain new and useful Improvements in Curtain-Roller Supports; and I do hereby declare that the following is a full, clear, and exact description of the invention, that will enable others skilled in the art to which it applies to make and use the same, reference being had to the accompanying drawings, and to the letters of reference marked thereon, which form a part of this specification.

Similar letters refer to similar parts in the several figures therein.

My invention relates to improvements in curtain-roller supports.

The objects of the invention are set forth in the following description.

Figure 1 of the drawings is a front elevation of a portion of a narrow curtain provided with my improved supports. Fig. 2 is a similar view showing the supports adjusted in a position different from that shown in Fig. 1. Fig. 3 is a similar view showing the supports adjusted in still another position. Fig. 4 is an end elevation of my improved supports in the position shown in the preceding figures, with the curtain and roller removed. Fig. 5 is a plan view of the guide-plate. Fig. 6 is a side elevation of same. Fig. 7 is the end elevation of same.

The roller B supports the curtain A, and is provided with end pivots, F, which find their supporting-bearings in the projections e from the slide-plates D. The slide-plates are provided with the longitudinal slots b, adapted to receive the screw S, by which they are bound to the wall-plates C, provided with slots a, adapted to receive the same screw. The wall-plates are also provided with the screw or nail holes d, one at each end, by which the plates are secured to the wall or window-casing. The two plates are secured together by means of the screw S, passing through the plate-slots and the nut E, in the position shown in Fig. 4. The wall-plate of each couple is thus secured in a convenient location on the wall or window-casing by means of screws or nails or in any well-known method. The pivots of the curtain-roller are thus inserted within their

bearings in the slide-plates and the latter slide to or from each other, as may be required to accommodate the position of the pivot-bearings to the length of the roller and the desired position of the curtain, after which the slides are bound firmly together by means of the screw and nuts, which prevent the slide-plate from sliding farther in either direction and cause the curtain and roller to be supported in the desired position.

Should it happen that the roller does not hang horizontal, the lower end can be easily raised by loosening the screw and sliding it upward in the slot in the wall-plate until the roller is horizontal, whereupon the screw is tightened again, which secures the parts in the desired position.

The vertical adjustment of either end of the roller is limited only by the length of the slot in the wall-plate. The horizontal or lateral adjustment of the curtain-roller is limited only by the length of the slots in the slide-plates; but the horizontal adjustment of the slide-plates has other uses. It affords means for supporting rollers of different lengths by the same wall-plates without disturbing their position and for the selection of suitable places for attaching the wall-plates without damage to moldings, as the position of the curtain and roller can be adjusted independently of the position of the wall-plates, limited only by the length of the slots in the slide-plates. For example, the wall-plates can be located close to the ends of the roller, as shown in Fig. 1, or at a considerable distance therefrom, as shown in Fig. 2, or at a point between these two extremes, as shown in Fig. 3. It is evident, also, that by adjusting the slide-plates in the various positions shown in said figures they can be arranged to support rollers of varying lengths without changing the position of the wall-plates.

By turning the slide-plates, one or both, around, as shown at the right-hand end of the roller in Fig. 3, a still greater variation in length of roller can be accommodated without disturbing the wall-plates.

When desired, a thin plate, G, provided with side flanges, g, projecting right-angularly from one side or face, and similar end flanges, g', projecting from the opposite side or back, may be interposed between the wall and slide

plates, as shown in Fig. 4, the plate being provided with a central perforation, g'' , adapted to receive the screw S.

The size of the plate and arrangement of the flanges is such that the wall-plate is contained between the flanges projecting from the back and the slide-plate between the flanges projecting from the face of the interposed plate. The slide-plate is thereby prevented from revolving upon the binding-screw when the latter is loosened, and renders it impossible for the relative angular positions of the wall and slide plates to be changed while in use.

The pivot-aperture e' in the slide-plate may be round, as shown by dotted lines in Fig. 4, or rectangular, as shown by the solid lines, to lock the spring of a spring-roller.

What I claim as new, and desire to secure by Letters Patent, is—

1. Curtain-roller bearings formed of longitudinally-slotted and crossing plates adjustable horizontally and vertically by screws and nuts, as shown and described.

2. The combination, with a slide-plate provided with screw-slot b and pivot-aperture e' , of a wall-plate provided with a slot, a , and screw-holes d , and a binding screw, S, and nut E, substantially as described, and for the purposes set forth.

In testimony whereof I have hereunto set my hand this 5th day of May, 1887.

GEORGE L. TYLER.
